REGENERATIVE HEAT EXCHANGER

William A. Morton, Pittsburgh, Pa., assignor to Sunbeam Engineering Corporation, Pittsburgh, Pa., a corporation of Pennsylvania

Continuation of application Ser. No. 257,504, Feb. 11, 1963. This application Aug. 30, 1965, Ser. No. 487,965

11 Claims. (Cl. 165—6)

The present invention relates to regenerative heat exchangers and, more particularly, to regenerative heat exchangers utilizing the heat from the exhaust gases of a furnace for preheating combustion air supplied to the furnace.

In furnaces of the type utilized for steelmaking and other applications wherein large amounts of heat at high temperatures are required, it is highly desirable to utilize the heat available in the exhaust gases for preheating the air supplied for combustion in the furnace in order to improve the efficiency and, consequently, reduce the operating costs.

One system presently in wide use for this purpose utilizes a pair of heat exchangers having regenerative material therein. Air for combustion is drawn into the furnace through one of the exchangers and the exhaust gases are passed out through the other exchanger, causing the regenerative material therein to be heated. The flow is then reversed with combustion air being drawn in through the exchanger which has just been heated by the exhaust gases and the exhaust gases passing out through the other exchanger heating it up. In the usual application, the flow is reversed about every fifteen minutes or so. This system has many disadvantages, i.e., high initial cost and low efficiency, but the main disadvantages are first the need for two rather than a single heat exchanger and the further disadvantage that the temperature of the preheated air is not constant, but gradually diminishes as the preheat chamber cools.

Another system used is a rotary-type heat exchanger having longitudinal flues therein which are heated by the exhaust gases passing through and then give up this heat to combustion air passing through as the exchanger is rotated. The exchanger is generally constructed of an alloy capable of withstanding high temperatures but, as yet, these types of exchangers are limited to around 1500 degrees F. whereas in many applications much higher temperatures are desirable.

Therefore, it is an object of the present invention to provide a new and improved regenerative-type heat exchanger which eliminates or greatly reduces one or more of the disadvantages of the aforementioned systems.

More specifically, it is an object of the present invention to provide a new and improved regenerative heat exchanger of the rotary type having longitudinal passages therein constructed with a regenerative material of a refractory type wherein the exhaust gases from the furnace move through the passages giving up heat which is later transferred to preheat combustion air moving through the passages as the exchanger rotates.

Another object of the present invention is to provide a new and improved regenerative heat exchanger of the type described wherein the passages carrying waste gases are purged of these waste gases during rotation, these waste gases being prevented from returning to the furnace, and those passages carrying combustion air which has been heated are purged of this heated air so it is not lost to the atmosphere but is channeled back so it may be supplied to the furnace or device associated with the regenerative heat exchanger.

The present invention has for another object the provision of a new and improved regenerative heat exchanger of the type described wherein waste gases having tem-

2

peratures of approximately 2500° F. may be utilized for preheating air to temperatures higher than with previous practice, whereby exchangers are capable of being utilized in high temperature applications not possible with the types previously mentioned.

Yet another object of the present invention is to provide a new and improved regenerative exchanger of the type described which is capable of heating large amounts of combustion air to a relatively constant temperature.

A further object of the present invention is to provide a new and improved regenerative heat exchanger of the type described having an insulated drum rotatable about either a horizontal or vertical axis containing a plurality of fluid passages constructed of a refractory material, in juxtaposition to non-rotating end plenum chambers and division walls positioned to sealingly engage the ends of the drum along a chord thereof to direct the flow of exhaust gases through one set of passages, and air to be preheated through another set of passages in a manner to effect a heat exchange between the regenerator materials and the fluids without appreciable mixing of the fluids and without appreciable loss of heat to the atmosphere.

A still further object of the present invention is to provide a new and improved regenerative heat exchanger of the type described in the preceding paragraph wherein new and improved means are provided for supporting the end baffles so as to maintain their relatively sealed engagement with the ends of the drum as the drum expands and contracts during heating and cooling.

Yet another object of the present invention is to provide a new and improved regenerative heat exchanger of the type described which is simple and economical of construction and operation, highly efficient in effecting heat transfer, relatively small in size and easy to maintain.

Further objects and advantages of the present invention will become apparent as the following description proceeds and the features of novelty which characterize the invention will be pointed out with particularity in the claims annexed to and forming a part of this specification.

The foregoing and other objects and advantages of the present invention are accomplished by the provision of a new and improved regenerative heat exchanger for effecting a heat transfer between fluids wherein there is provided an insulated rotating drum having a plurality of separate longitudinal passages therein constructed of a refractory material capable of withstanding extremely high temperatures. The drum is positioned to rotate about its longitudinal axis and there are provided at the opposed ends of the drum nonrotating baffles, each in peripheral sealing engagement with an end of the rotating drum. Each of the baffles is provided with an inlet and an outlet which are separated by a division wall or center post. The inlet of one baffle is positioned to be in continual communication with the outlet of the other baffle through a plurality of the passages in the drum as it rotates, thus providing for the movement of gases into and out of the heat exchanger. The inlet of the other baffle is in continual communication with the outlet of the one baffle through a plurality of passages in the drum as it rotates, thus likewise providing for the movement of gases through the exchanger in the opposite direction. Combustion air to be preheated passes through the inlet of one baffle and the passages of the rotating drum which have previously been heated by the passage of exhaust gases therethrough, thus effecting a heat exchange between the gases to preheat the combustion air.

The center posts or division walls of the baffles are positioned in parallel relation to one another at opposed ends of the drum. Each of the posts is provided with passage means; the passage means in one of the baffles

being in communication with the air inlet thereof and a plurality of the passages in the rotating drum, and the passage means in the other baffle being in communication with the waste gas inlet thereof and a plurality of passages in the rotating drum. Each of the center posts is provided with means for purging the passages in the rotating drum as they pass in line with the posts, the purging means in each center post being in communication with the passage means in the opposite posts so that the purging fluid will be directed through the passages in the drum and out the passage means in the posts. In one case the purging means prevents waste gases from being returned to the furnace and in the other case prevents heated combustion air from being lost to atmosphere.

Other features of the invention include means which support one of the baffles so that it can move longitudinally with the drum in order to maintain the peripheral sealing engagement between the end of the drum and the baffles as the drum elongates and contracts due to heating and cooling. Additionally, new and improved rotary seals are provided between the drum ends and the baffles so that gases within the drum do not escape therefrom in excessive amounts. Also the ends of the fluid passages in the rotating drum are tapered in order to reduce leakage between adjacent passages while providing minimum clearance between the baffles and the drum.

For a better understanding of the present invention, reference may be had to the accompanying drawings wherein:

FIG. 1 is a top plan view of a furnace system employing a new and improved regenerative heat exchanger constructed in accordance with the features of the present invention;

FIG. 2 is a side elevational view of the apparatus of FIG. 1;

FIG. 3 is a somewhat enlarged sectional view taken substantially along line 3-3 of FIG. 1;

FIG. 4 is a sectional view taken substantially along line 4-4 of FIG. 3, assuming that FIG. 3 shows the complete structure;

FIG. 5 is a sectional view taken substantially along line 5-5 of FIG. 3, again assuming that FIG. 3 shows the complete structure;

FIG. 6 is a somewhat enlarged sectional view taken substantially along line 6-6 of FIG. 2;

FIG. 7 is an enlarged sectional view taken substantially along line 7-7 of FIG. 2;

FIG. 8 is an enlarged sectional view taken substantially along line 8-8 of FIG. 2;

FIG. 9 is a sectional view taken substantially along line 9-9 of FIG. 7, assuming that FIG. 7 shows the complete structure;

FIG. 10 is a sectional view taken substantially along line 10-10 of FIG. 8, assuming that FIG. 8 shows the complete structure;

FIG. 11 is an enlarged fragmentary sectional view taken substantially along line 11-11 of FIG. 2;

FIG. 12 is an elevational view, with certain portions cut away, illustrating another embodiment of the present invention;

FIG. 13 is a sectional view taken on line 13-13 of FIG. 12, assuming that FIG. 12 shows the complete structure; and

FIG. 14 is a sectional view taken on line 14-14 of FIG. 12, again assuming that FIG. 12 shows the complete structure.

Referring now to the drawings, there is illustrated a furnace system 12 including the regenerative heat exchanger 13 which is constructed in accordance with the features of the present invention. In a typical application, the exchanger 13 is utilized for preheating combustion air supplied to a high temperature furnace 14 through an inlet duct 15. The high temperature waste gases or products of combustion from the furnace 14

pass from the furnace through an outlet duct 16 into the exchanger 13 whereby heat is extracted therefrom for use in preheating the combustion air supplied to the furnace through inlet duct 15.

Essentially, the heat exchanger 13 comprises a rotating drum 18 containing a heat regenerative material which is supported from a suitable structure such as the base 20 (FIGS. 2, 6, 7 and 8) for rotation about a horizontally disposed longitudinal axis. An end baffle 22 is positioned in peripheral sealing engagement with the end of the rotating drum 18 adjacent the furnace 14 for directing preheated combustion air from the drum to the inlet duct 15 of the furnace and for directing the waste gases from the outlet duct 16 of the furnace into the rotating drum 18. At the other end of the drum 18 there is provided another end baffle 24 which is positioned in peripheral sealing engagement with the corresponding drum end for directing combustion air to be preheated into the drum and directing waste gases from the drum to an exhaust stack 25.

The drum 18 is constructed of an outer cylindrical shell 26 of steel plate and is provided with an internal lining 28 of insulating material for preventing the steel shell from overheating due to the extremely high temperatures within the drum. The lining 28 extends almost the entire length of the shell stopping short of the ends as shown in FIG. 3. Angle flanges 30 and 32 are provided at the ends of the drum for stiffening the shell or drum 18 and providing support for radially disposed annular end face plates 34 and 36 which are secured thereto.

In order to provide for the passage of combustion air and waste gases through the drum and to preheat the combustion air and extract heat from the waste gases, drum 18 is provided with a plurality of separate longitudinal fluid passages 38. The walls of these passages are formed of a refractory material, such as fire brick 40, having a high magnesia content in order to withstand temperatures as high as 3000° F. The fire bricks are provided with V-shaped edges (FIGS. 4 and 5) and are arranged to form passages of square or rectangular cross section as shown in FIGS. 4 and 5 of the drawings with the joints staggered longitudinally, as shown in FIG. 3. The individual bricks are cemented together with a refractory cement and, thus, form an integral structure within the drum 18. The central passages formed by the fire brick are not utilized, as will become apparent from the ensuing description, and are plugged at the ends with plugs 42 of refractory material to prevent fluid passage through these central passages. It should be noted that the V-shaped edges of the fire brick 40 dovetail together nicely to provide a passage structure that is strong and easy to construct. Additionally, the fire bricks at both ends are provided with V-shaped ends 40a which lie in a plane with end face plates 34 and 36 and reduce the friction of the entering air or waste gas.

For the purpose of supporting the fire brick structure within the drum 18, the structure is surrounded by a refractory lining 44 which is preferably of a castable type refractory material. The lining 44 serves to securely hold the fire brick structure and the insulation lining 28 in place within the shell 26 of drum 18 to rotate therewith. It should be noted from FIG. 3 that the lining 44 is provided with end flanges 44a which extend outwardly to engage the interior of the shell 26 between the ends of the insulation lining 28 and the inside faces of the end face plates 34 and 36. This construction serves to bond the whole internal structure of the drum tightly within the shell 26. The outer end faces 44b of the lining 44 are flush with the outer faces of the face plates 34 and 36 in order to provide smooth surfaces which are in interfacing relation with the end baffles 22 and 24.

To support the drum 18 for rotation, it is provided with a plurality of annular tracks 46, 48 and 50 which are spaced appropriately along the length of the drum. These tracks additionally serve as stiffeners for the drum

and the number of tracks needed depends on the thickness of the shell 26, the length of the drum and its weight. Tracks 46 and 48 have sufficient width to permit substantial movement of the drum with longitudinal expansion and contraction thereof.

Each of the tracks is supported for rotation on two pairs of rollers 52 (FIG. 6) and each pair of rollers is carried by a bracket 54 which is pivotally mounted on a hinge bracket 56 secured to the frame 20. The brackets 56 can be adjusted inwardly or outwardly on the frame to compensate for the wear on the tracks and rollers. The track 50, which is closest to the furnace end of the drum 18, is provided with a pair of small annular flanges 50a which form a channel-shaped recess on the outer surface of the track in which the rollers 52 ride, thus effectively anchoring the furnace end of the drum 18 and requiring expansion to be taken care of by movement of the stack end of the drum. Thus, the tracks 46 and 48 are not provided with flanges thereby accommodating such expansion and contraction of the drum 18 as it is heated and cooled.

For the purpose of rotating the drum 18 in typical applications (as indicated by the arrows in FIGS. 1, 2, 6, 7 and 8) there is provided an electric motor 56 which is drivingly connected to a right angle-type gear reducer 58 having an output shaft 58a extending parallel to the longitudinal axis of the drum. The gear reducer 58 is coupled to the motor 56 through an adjustable gear reducer 60 (FIG. 6) having a control handle 60a for varying the speed ratio thereof in order to rotate the drum 18 at the desired speed. The output shaft 58a is connected by any suitable means, such as a chain or belt drive 61, to a shaft 62 which is journaled in the brackets 57 and extends longitudinally parallel with the drum 18. The shaft 62 is drivingly connected to the rollers 52 by means of chain, belt or other suitable drives 64 to rotate the rollers 52 and thus drive the drum.

The furnace end baffle 22 (FIGS. 8 and 10) comprises an outer cylindrical shell 66 of a diameter equal to the shell 26 and a circular back plate 68 welded thereto. The circumferential edge of the shell 66 facing the drum is provided with an angle ring stiffener 70 to which is attached an annular face plate 72 of the same dimensions as and positioned to face the face plate 34 on the rotating drum 18. Between these two face plates there is provided a sealing ring 74 which is constructed of asbestos or other material having heat resistant qualities and a relatively low coefficient of friction. The seal ring 74 is attached to the face plate 72 and the baffle 22 is positioned so that the outer face of the seal ring closely abuts the face plate 34 on the drum 18, thus providing a rotary seal between the drum and baffles which is capable of withstanding high temperatures. Since the furnace end of drum 18 is effectively fixed with respect to longitudinal movement, the baffle 22 is fixedly supported in position by means of side braces 76 and the end brace 78 which are attached to the frame 20.

The interior of the baffle 22 is lined with a refractory material 80 which is preferably of a castable-type refractory material and is integrally cast within the baffle to form an outlet cavity 82 and an inlet cavity 84 (FIG. 8) which are separated by a center post 86. These cavities are generally semicircular in cross section and each is in continual communication with a little less than half of the passages 38 in the rotating drum; the few remaining passages in the drum being positioned in front of the center post 86. The outlet cavity 82 is provided with a rearwardly extending outlet duct 88 which is also lined with the refractory material 80 and is connected to the inlet duct 15 of the furnace 14 by means of a duct 90 which is also lined with refractory material. The inlet cavity 84 is provided with an enlarged inlet duct 92 also lined with the refractory material 80 which is connected to a refractory lined duct 94 attached to the outlet duct 16 of the furnace 14. The larger furnace outlet duct 16 and

ducts 92 and 94, as compared with furnace inlet duct 15 and ducts 88 and 90, is to take care of the variation in volume with heating of the air or gases involved due to temperature.

For purging purposes, the center post 86 of furnace end baffle 22 is provided with a plurality of spaced-apart purging nozzles 96 which are positioned in a vertical center line above the axis of drum rotation and are directed to blow streams of clean air or other gas into the passages 38 of the drum which have just been carrying waste gases as they pass in front of the nozzles as the drum rotates. This purging air is exhausted at the other end into the waste or exhaust gas duct leading to stack 25, as described hereinafter. Diametrically opposite to the nozzles 96 there are provided a plurality of purged gas receiving passageways 98. These passageways are of L shape and positioned to receive purging gas directed into the passages 38 from the other end of the drum which have just been carrying waste gases and are in communication with the cavity 84 so that these waste gases do not return to the furnace but mix with the waste gases coming from the furnace through duct 16.

Similarly, the stack end baffle 24 (FIGS. 7 and 9) has an outer cylindrical shell 100 of a diameter equal to that of shell 26 of the drum 18 and a back plate 102 joined thereto. The periphery of the shell 100 facing the drum is provided with a stiffening angle ring 104 and an annular face plate 106 of dimensions equal to the stack end face plate 36 of the drum 18. There is also provided a sealing ring 108 similar to the ring 74 for effecting a rotary seal between the drum 18 and the baffle 24.

In order to maintain a tight seal with the stack end of drum 18 as it expands and contracts, the stack end baffle 24 is supported on a rolling cradle 110 having guide rollers 112 which roll on angle tracks 114 provided on the base 20. The baffle is attached to the cradle by a pair of side braces 116 and an end brace 118 which maintain the stack baffle 24 in a vertical plane as it moves horizontally with the cradle 110. Means such as a pair of tension springs 120 which are connected to the frame 20 and the side braces 116 may be provided for continually biasing the baffle 24 toward the drum and for maintaining the cradle centered on the tracks. Thus, the rotary seal comprising element 108 between the baffle 24 and the drum 18 is continuously maintained regardless of the expansion or contraction of the drum as it is heated or cooled.

The interior of the baffle 24 is lined with a refractory material 122 which is preferably of the castable type and is molded to form an inlet cavity 124 and outlet cavity 126 which are separated by a center post 128. These cavities are also generally semicircular in cross section and each is continually in communication with a little less than half of the passages 38 in the rotating drum; the few remaining passages in the drum being positioned in front of the center post 128.

The cavity 124 is provided with an extended inlet duct 130 which is lined with the refractory material 122 and connected to a source of combustion air 132 by means of a slip joint 134 in order to accommodate the movement of the baffle. The cavity 126 is provided with an extended outlet duct 136 lined with the refractory material 122 and connected to the exhaust stack 25 by means of a duct 138 and slip joint connection 140.

The center post 128 of stack end baffle 24 is provided with a plurality of purge nozzles 142 which are positioned directly opposite the L-shaped passageways 98 in the center post 86 of the opposed furnace end baffle 22 in order that the purging air from these nozzles will pass through the passages 38 in the rotating drum which have just been carrying waste gases to purge them of these waste gases and prevent these gases from entering the furnace. To this end these purged waste gases enter the passageways 98 and flow into the cavity 84 and eventually out the exhaust stack 25. L-shaped passageways 144 are provided in the center post 128 and are aligned oppo-

site the purging nozzles 96 in the opposite furnace end baffle 22 in order to receive the purging gas from these nozzles through the passages 38 in the drum 18 which have been carrying clean inlet air which has been heated and is now trapped between posts 86 and 128. In order not to waste the heat in this trapped air, passageways 144 are in communication with the inlet cavity 128 in order to return the heated combustion air into the combustion air leading to the furnace.

In operation, combustion air to be preheated passes through the inlet duct 130 into the inlet 124 of the stack end baffle 24. The air then moves down the passages 38 of the rotating drum which are at elevated temperatures because of the waste gases of high temperatures which have just previously passed therethrough. The fire brick 40 comprising the walls of the passages 38 acts as a regenerator in that it accepts and holds heat given up by the waste gases and then gives up this heat to the combustion air.

The preheated combustion air from the drum passages 38 then passes into the outlet cavity 82 of the furnace baffle 22 and into the furnace 14 through the outlet duct 88, duct 90 and inlet furnace duct 15. High temperature waste gases, the products of combustion of the furnace, pass from the furnace through the outlet duct 16, duct 94, and inlet duct 92 into the inlet cavity 84 of the furnace end baffle 22. These high temperature gases then pass through the passages 38 of the rotating drum in the opposite direction to the flow of combustion air through the passages causing the passage walls to heat up and, consequently, lowering the temperature of these gases as they reach the end of the drum 18 and enter the cavity 126 in the stack end baffle 24. The heat given up by the waste gases in the passages 38 is stored in the refractory fire brick 40 and is transferred to the combustion air passing through the passages in the other direction. The waste gases in the outlet cavity 126 after giving up heat in the passages 38 then pass through the outlet duct 136, duct 138 to the stack 25. Thus, a great amount of heat available from the waste gases, which would otherwise be exhausted to the stack 25, is utilized to preheat the combustion air entering with a consequently resulting higher efficiency and lower operating cost for the furnace. The general direction of air flow is shown by the arrows in FIG. 1.

The center posts 86 and 128 serve as seals dividing the hot and cold sides of the drum and prevent any appreciable dilution of the combustion air with waste gases or the loss of heat by diverting hot combustion air to the stack. The purging nozzles 96 and 142 introduce a small quantity of high velocity air down the passages 38 as they rotate in front of the nozzles 96 and 142. This air is of higher pressure than either the waste gases or combustion air and, thus provides an effective air seal for preventing intermixing. The passageways 98 and 144 are positioned opposite these nozzles in the respective center posts and are vented to the cavities 84 and 126, respectively. Thus, with respect to purging nozzles 142, which cause purging air to pass through passages 38 which have just been carrying waste gases, they force these waste gases trapped in these passageways between posts 86 and 128 into L-shaped passages 98 and then into cavity 84, which is in the waste gas side of the drum, and out of the stack 25 without intermixing or diluting the fresh combustion air. With respect to purging nozzles 96, they cause purging air to pass through passageways 38 which have been carrying clean combustion air and which have heated combustion air trapped therein between posts 86 and 128. So that the heat in this air is not lost to atmosphere, it is received by L-shaped passageways 144 and led into cavity 128 so as to mingle with incoming combustion air to be heated by the hot walls of passageways 38.

During each rotation of the drum, each of the passages 38 therein has high temperature waste gases passed there-

through causing the walls to absorb heat. As these passages move in front of the purging nozzles 142, the waste gases contained therein are diverted by passageways 98 into the waste gases entering cavity 84. After this, fresh combustion air is passed through these purged passageways 38 which give up their heat to preheat this combustion air.

In this manner the passages 38 are continually purged either of waste gases diverted to the stack, or heated combustion air which is saved by returning it to the combustion air supply as the drum 18 rotates. Moreover, since the drum is insulated and the passages are constructed of refractory material rather than an alloy, temperatures as high as 3000° F. can be maintained. Additionally, only a single drum is needed and the temperature of the preheated air is relatively constant once equilibrium is attained. The drum is supported for rotation by external tracks with no center shaft being required and the speed of the drum can be adjusted as desired. Moreover, the V-shaped ends 40a greatly reduce any friction between the drum 18 and the baffles 22 and 24 while providing a good fluid seal therebetween.

When the unit is fired up, the drum will expand and this expansion is readily taken care of by the supporting rollers and the movable baffles 24 with no loss in sealing efficiency at the ends of the drum as the seal between the drum and the end baffles is constantly maintained regardless of whether the drum is expanding or contracting in length.

Referring now to FIGS. 12, 13, and 14 of the drawings, there is illustrated another embodiment of the present invention wherein a vertical arrangement of a furnace system including a furnace and rotary heat exchanger is illustrated. The corresponding parts of FIGS. 12, 13 and 14 are designated by the same reference numerals as in the preceding embodiment. For the purpose of providing support for the furnace 14 which, in FIG. 12 of the drawings, is illustrated as being the topmost unit in the vertical arrangement of the system, there is provided a platform 150. Suitable means 151 are illustrated as securing the furnace 14 to the platform 150.

The regenerative heat exchanger is designated as 13' in FIGS. 12 to 14 of the drawings. This heat exchanger 13' may be substantially identical with the regenerative heat exchanger 13 described above, and the corresponding parts thereof are designated by the same reference numerals as in the preceding drawings. The relationship of the upper end of the heat exchanger 13' to the end baffle 22 is identical with that previously described, and the connections between the furnace 14 and the end baffle 22 are also identical with those previously described and are designated by the same reference numerals.

It will be appreciated that since the drum 18' of heat exchanger 13' is vertically disposed, the annular tracks 46, 48 and 50 are no longer necessary and are eliminated. Whether the drum 18' is mounted vertically or horizontally, however, expansion and contraction thereof will still result. Consequently, provision must be made to accommodate such expansion and contraction. In the embodiment previously described, the furnace 14 was fixed as was the baffle 22, and expansion and contraction of drum 18 relative to the other baffle 24 was required. In the arrangement disclosed in FIG. 12, the end baffle 24' is secured to a stationary supporting structure. Consequently, relative movement between the upper end of the drum 18' and the associated parts including the furnace 14 and the baffle 22 must be provided. To this end the platform 150 is supported on suitable adjustable supports 153 which might be in the nature of jacks or the like. With this arrangement the furnace 14 and the baffle 22, which may be connected thereto, can be raised or lowered as the expansion of the drum 18' requires. It will be appreciated that such adjustment of the supports 153 may be automatically made in response to suitable control means or might be manually adjusted. It will be appreciated

that once steady state operating conditions are reached, the length of drum 18' remains constant and supports 153 will be adjusted to raise furnace 14 to give the desired clearance when the unit has initially warmed up.

To support the drum 18' for rotation, there is provided at the lower end thereof an annular platform 154 which is secured to the shell 26 of the drum 18' by a multitude of brace means generally designated at 155. The annular platform 154 and, consequently, the drum 18' secured thereto are supported for rotation on a plurality of supporting and driving rollers 156 mounted for rotation on suitable supports 157 spaced around the platform 154, as best shown in FIG. 13 of the drawings, and in turn supported on a suitable supporting structure or framework 158. Preferably the rollers are adjustable to assure vertical alignment of the drum 18'. A suitable prime mover, generally designated at 160, through gear reduction means 161 and drive means 162, 163 and 164, drives some or all of the rollers 156 at the desired speed of rotation of the drum 18'. As illustrated in FIG. 13 of the drawings, two of the rollers on diametrically opposed sides of the drum are driven by the prime mover 160 and are driving as well as supporting rollers.

To provide the desired support for the refractory structure contained within the shell 26 of drum 18', such as the insulating lining 28, the refractory lining 44 and the fire brick 40 defining the longitudinal fluid passageways 38, some modification in the lower end of the drum 18' is required as contrasted with that of the horizontal arrangement previously described. As best shown in FIG. 12 of the drawings, an arched construction, generally designated at 165, is provided to support the downward forces exerted by the center portion of the refractory heat exchange material. This arched construction 165 still insures that the passageways 38 through the heat exchanger are permitted to connect with the baffle cavities 124' and 126' defined in lower end baffle 24'. The baffle 24' is very similar to the baffle 24 described above, but since it is supported on the end thereof an inlet opening 167 leading to the cavity 124' is connected to the inlet duct 130 (not shown). Similarly, the cavity 126' is provided with an outlet opening 168 connected to the outlet duct 136 (not shown). The cavities 124' and 126' are lined with the refractory material 122' identical with that lining the cavities in baffle 24 previously described. The center post 128' of the end baffle 24' is provided with a plurality of purge nozzles 142 and the L-shaped passageway 144 previously described.

In view of the detailed description included above, the operation of the system disclosed in FIGS. 12, 13 and 14 will be readily understood by those skilled in the art and no further discussion is included herewith.

While there have been illustrated and described several embodiments of the present invention, it will be appreciated that numerous changes and modifications will occur to those skilled in the art, and it is intended in the appended claims to cover all those changes and modifications as fall within the true spirit and scope of the present invention.

What is claimed as new and desired to be secured by Letters Patent of the United States is:

1. A regenerative heat exchanger for effecting a heat transfer between fluids of different temperatures, comprising a rotating drum containing a plurality of separate longitudinal fluid passages constructed of refractory material, means for rotating said drum, a pair of opposed end baffles, each in peripheral sealing engagement with an end of said drum, each of said baffles having an inlet and an outlet separated by a center post, the inlet of one baffle positioned to be in continual communication with the outlet of the other baffle through a plurality of said fluid passages and the inlet of said other baffle positioned to be in continual communication with the outlet of said one baffle through a plurality of said fluid passages as the drum is rotated, said center posts positioned

parallel to each other and each having passage means defined therein, said passage means in one of said baffles being in communication with the inlet thereof and a plurality of fluid passages in said drum, said passage means in the other of said baffles being in communication with the inlet thereof and a plurality of fluid passages in said drum, and fluid passage purging means carried in each post, said purging means in each post positioned opposite said passage means in the other post for purging a plurality of fluid passages in said drum.

10 2. Apparatus as defined in claim 1 wherein said purging means include a plurality of nozzles positioned to direct a high-velocity flow of purging fluid into said passages as they pass in front of said nozzles during rotation of the drum.

15 3. A regenerative heat exchanger for effecting a heat transfer between fluids of different temperatures, comprising a rotating drum of regenerative material having a plurality of noncommunicating fluid passages extending

20 parallel to the axis of rotation of said drum, means for rotating said drum, a first end baffle in peripheral sealing engagement with one end of said rotating drum, a second end baffle in peripheral sealing engagement with the other end of said rotating drum, means supporting said second baffle for movement in the direction of the longitudinal axis of the drum to maintain said baffle in said peripheral sealing engagement with said rotating drum as said drum expands and contracts in length during heating and cooling thereof, each of said baffles having an inlet and an outlet

25 separated by a center post, the inlet of one baffle positioned to be in continual communication with the outlet of the other baffle through a plurality of said fluid passages and the inlet of said other baffle positioned to be in continual communication with the outlet of said one

30 baffle through a plurality of said fluid passages as the drum is rotated, said center posts positioned parallel to each other and each having passage means defined therein, said passage means in one of said baffles being in communication with the inlet thereof and a plurality of fluid

35 passages in said drum, said passage means in the other of said baffles being in communication with the inlet thereof and a plurality of fluid passages in said drum, and fluid passage purging means carried in each post, said purging means in each post positioned opposite said

40 passage means in the other post for purging a plurality of fluid passages in said drum as the passages pass in front of said center posts during rotation of said drum.

4. A regenerative heat exchanger for effecting a heat transfer between fluids of different temperatures, comprising a rotating drum of regenerative material having a plurality of noncommunicating fluid passages therein extending parallel to the axis of rotation of the drum, said drum being of substantial length whereby thermal expansion and contraction causes appreciable changes in length,

50 means for rotating said drum, said drum having an outer steel shell and said passages constructed of refractory material forming an integral internal structure supported within said shell to rotate therewith, means adjacent one end of said drum and restraining it against axial movement, the other end of said drum being free to move axially in response to thermal expansion and contraction of the drum, a first stationary end baffle in peripheral sealing engagement with the restrained end of said rotating drum, a second end baffle in peripheral sealing engagement with the other end of said rotating drum, means supporting said second baffle for movement in the direction of the axis of the drum to maintain said baffle in said peripheral sealing engagement with said rotating drum as said drum expands and contracts in length during heating and cooling thereof.

55 5. Apparatus as defined in claim 4 wherein the refractory material comprises brick shaped to form tongue and groove means between adjacent brick for forming an integral structure.

60 6. A regenerative heat exchanger for effecting a heat transfer between fluids of different temperatures, comprising a rotating drum of regenerative material having a plurality of noncommunicating fluid passages therein extending parallel to the axis of rotation of the drum, said drum being of substantial length whereby thermal expansion and contraction causes appreciable changes in length,

65 means for rotating said drum, said drum having an outer steel shell and said passages constructed of refractory material forming an integral internal structure supported within said shell to rotate therewith, means adjacent one end of said drum and restraining it against axial movement, the other end of said drum being free to move axially in response to thermal expansion and contraction of the drum, a first stationary end baffle in peripheral sealing engagement with the restrained end of said rotating drum, a second end baffle in peripheral sealing engagement with the other end of said rotating drum, means supporting said second baffle for movement in the direction of the axis of the drum to maintain said baffle in said peripheral sealing engagement with said rotating drum as said drum expands and contracts in length during heating and cooling thereof.

70 7. Apparatus as defined in claim 4 wherein the refractory material comprises brick shaped to form tongue and groove means between adjacent brick for forming an integral structure.

75 8. A regenerative heat exchanger for effecting a heat transfer between fluids of different temperatures, comprising a rotating drum of regenerative material having a plurality of noncommunicating fluid passages therein extending parallel to the axis of rotation of the drum, said drum being of substantial length whereby thermal expansion and contraction causes appreciable changes in length,

transfer between fluids of different temperatures, comprising a rotating drum, said drum being of substantial length whereby thermal expansion and contraction causes appreciable changes in length, means for rotating said drum, annular end flanges at the ends of said drum having radial faces, refractory means defining a plurality of separate open ended longitudinally extending fluid passages in said drum, means adjacent one end of said drum and restraining it against axial movement, the other end of said drum being free to move axially in response to thermal expansion and contraction of the drum, a first end baffle in peripheral sealing engagement with the restrained end of said drum, a second end baffle in peripheral sealing engagement with the opposite end of said drum, each of said baffles having an inlet and an outlet separated by a center post, annular end flanges on both of said baffles having radial faces, faces on said baffles positioned to face in close proximity the faces on the respective ends of said drum to provide said peripheral sealing engagements therewith, the inlet of said first baffle positioned to be in continual communication with the outlet of said second baffle through said fluid passages and the inlet of said second baffle positioned to be in continual communication with the outlet of said first baffle through said fluid passages as the drum is rotated, said center posts being positioned parallel to each other and effectively closing both ends of said fluid passageways.

7. Apparatus as defined in claim 6 wherein there are provided annular seals of heat resistant material, said seals being interposed between the end faces on said drum and the respective end faces on said baffles.

8. Apparatus as defined in claim 7 wherein said seals are comprised of asbestos material and are fixedly secured to the respective end faces on said baffles.

9. A regenerative heat exchanger for effecting a heat transfer between fluids of different temperatures, comprising a rotating drum, said drum being of substantial length whereby thermal expansion and contraction causes appreciable changes in length, means for rotating said drum, refractory means defining a plurality of separate open ended longitudinally extending fluid passages in said drum, said drum having an outer steel shell, a fixed support base underlying said drum having a plurality of rollers mounted for rotation thereon, radially positioned annular track means secured to the exterior of said shell adjacent one end thereof and engaging said rollers on said base for rotatably supporting said drum whereby one end of said drum is restrained against axial movement and the other end of said drum is free to move axially in response to thermal expansion and contraction of the drum, a first end baffle in peripheral sealing engagement with the restrained end of said drum, a second end baffle in sealing engagement with the opposite end of said drum, each of

said baffles having an inlet and an outlet separated by a center post, the inlet of said first baffle positioned to be in continual communication with the outlet of said second baffle through said fluid passages and the inlet of said second baffle positioned to be in continual communication with the outlet of said first baffle through said fluid passages as the drum is rotated, said center posts being positioned parallel to each other and effectively closing both ends of said fluid passageways.

10. Apparatus as defined in claim 9 including means for driving at least some of said rollers to rotate said drum.

11. A regenerative heat exchanger for effecting heat transfer between fluids of different temperatures comprising a vertically positioned rotating drum of substantial length and including a refractory arch structure positioned in the lower end of said drum, refractory means supported by arch structure and defining a plurality of separate open-ended longitudinally extending fluid passages in said drum, said drum having an outer steel shell, a fixed support base underlying said drum, a plurality of rollers positioned rotatably to support said drum upon the support base adjacent the lower end of said drum whereby the lower end of said drum is in substantially fixed vertical position and the upper end of said drum is free to move axially in response to thermal expansion and contraction of the drum, a lower end baffle in peripheral sealing engagement with the lower end of said drum, a second end baffle in sealing engagement with the upper end of said drum, the lower baffle having a centrally positioned wall extending therethrough in close proximity with the arch structure and dividing the lower end baffle into inlet and outlet sections, the upper said baffle having means dividing it into inlet and outlet sections, the inlet and outlet sections of said upper end baffle being in continuous communication with the outlet and inlet sections respectively of the lower end baffle through fluid passages within the drum and extending therebetween.
